HAROLD I. HUEY, OF SAYLESVILLE, RHODE ISLAND, ASSIGNOR TO SAYLES FINISHING PLANTS INC., OF SAYLESVILLE, RHODE ISLAND, A CORPORATION OF RHODE ISLAND.

METHOD OF AND APPARATUS FOR FEEDING FABRICS.

Application filed July 2, 1926. Serial No. 120,225.

The present invention relates to the treatment of fabrics to impart desired properties to the same, and more particularly to a method of and apparatus for feeding the fabric so that successive portions of the fabric will be subjected to an uniform time treatment.

In treating a fabric to impart a desired finish to the same or desired properties to the fabric, it is often desired to feed the fabric continuously while it is being subjected to the different treatments, but in many cases it is necessary to allow a time interval to elapse between different treatments. If the time interval is very short the same may be provided by passing the fabric around several rolls or guides while traveling from one place of treatment to another, but if a relatively long time interval is required to elapse between the successive treatments it may be necessary to slow down the speed at which the fabric is advanced or to provide means for supporting a long strip of fabric traveling from one place of treatment to another.

If it is unnecessary to keep the fabric in a stretched condition during the period between successive treatments the traveling fabric may be deposited in a receptacle or container in which it may remain for the desired period, but fabrics that need to be held in a stretched condition during the treatment period cannot be deposited in a receptacle in the manner just mentioned.

In order to keep a sheet of fabric in a stretched condition during the period required to elapse between treatments various forms of devices known as "continuous agers" have been proposed heretofore. These devices usually consist of a number of fabric supporting rolls arranged in staggered relation so that the fabric travels along a zigzag path in passing around the different rolls. Such proposed devices work very well where the length of fabric required to be maintained in a stretched condition is relatively short, but if a long strip of fabric is required to be maintained in a stretched condition the number of staggered rolls required to support the fabric and the space which the rolls occupy may be excessive.

Having the foregoing in mind the present invention relates to a fabric advancing device or "continuous batcher" which is ex-

treinely simple in construction, and which 55 consists of but few parts, while at the same time it will maintain in a stretched condition a traveling sheet of any length.

The principal feature of the invention resides in the method of and apparatus for 60 handling a fabric whereby a plurality of coils or layers of the fabric are advanced as a unit around their supporting structure, and fresh portions of the fabric are wound about the support at one side of the traveling layers while corresponding portions of the fabric are led off from the opposite side of the group of layers. In this manner the fabric is fed continuously from a source of supply around the coil supporting means 70 and then off from the traveling coils, and since as many coils as desired may be wound about the supporting structure a fabric of any desired length may be held in a stretched condition while traveling about the structure. 75

The path in which the coils of the fabric travel may be made as long as desired, and another feature of the invention resides in the construction whereby the source of fabric supply, and if desired a fabric treating device, are supported within the space enclosed by the traveling coils. 80

Still another feature of the invention resides in the construction whereby the coils 85 travel within a closed air-tight chamber so that they may be treated while in said chamber to a gas confined therein.

The foregoing and other features of the invention will be best understood from the 90 following description and accompanying drawings showing good practical means for carrying out the invention.

In the drawings:

Fig. 1 is a vertical sectional view through 95 a construction for carrying out the present invention;

Fig. 2 is a sectional view taken on the line 2-2 of Fig. 1; and

Fig. 3 on a reduced scale is a view similar 100 to Fig. 1 but shows a modified construction.

The supporting means upon which the traveling coils of fabric are wound may be varied in size and shape as desired, and the coils may travel within a closed passage, or 105 may be exposed as deemed advisable.

In the construction shown the coils of the fabric F are supported by the spaced rolls

10 that are arranged to form an enclosure in which the source of fabric supply 11 may be mounted. The rolls 10 are rotatably supported by a frame of any desired construction and they are provided with the stub shafts 12 that rotate in suitable bearings carried by said frame.

The rolls 10 in the present construction are supported within a closed endless passage 13, and it should be noted that a portion of the passage 13 extends below the floor X of the building while the upper portion of this passage is located a substantial distance above said floor. As a result of 10 this construction the passage 13 encloses a space or chamber in which means for supporting and treating the fabric F may be mounted. The walls 14 of the passage 13 may be formed of wood, metal, concrete, or 15 any other material found desirable or necessary to resist the action of the liquid or gases that may be employed in treating the fabric F while passing through the passage.

In the construction shown the fabric F to 20 be treated is unwound from the supply roll 11 supported by the frame 15, and it passes over suitable guide rolls 16 and feed rolls 17 to a treatment tank 18 where it is immersed in the desired liquid. The fabric 25 upon leaving the tank 18 passes between the squeeze rolls 19 and 20, one of which may be adjusted relatively to the other by the hand wheel 21 and is forced toward the other roll by the weight 22.

30 The fabric F passes from the roll 20 about one of the coil supporting rolls 10 and then about the series of rolls 10 to form any desired number of spiral coils, and the fabric passes from the outermost coil about a roll 35 to any desired means such as a device 40 for subjecting the fabric to its next treatment. It will be understood that the plurality of coils of the fabric travel as a unit relatively to their supporting rolls and that the unwinding portion of the fabric passes 45 continuously out of the passage 13 about the roll 23 while a fresh portion of the fabric passes continuously into the chamber from the roll 20. In this manner the passage of 50 the fabric around the chamber 13 is a continuous operation and each portion of the fabric is subjected to a uniform time treatment while passing from the roll 20 to the roll 23.

55 It may be desirable to drive the rolls 10 to thereby help advance the coils of the fabric about the chamber 13, and to this end each of the rolls 10 may have a sprocket 24 secured outside of the passage to a projecting stub shaft. The different sprockets may be driven by an endless chain 25 the tension of which may be varied by adjusting the chain tightening sprocket 26. The chain 25 may be driven by any suitable means such 60 as an electric motor 27 having a worm wheel

28 that drives a belt or chain 29 which in turn drives the belt or chain 30.

The construction described, whereby any desired number of layers of the fabric may be wound upon the rolls 10 and advanced 70 as a unit relatively to said rolls, not only constitutes an extremely simple and satisfactory construction for maintaining a traveling sheet of fabric of any desired length in a stretched condition, but since the different coils or layers of the fabric are laid one over the other in contact with each other, the engagement of one coil with another helps to keep the sheets from contracting or shrinking in a direction transversely of 75 the fabric.

If a large number of coils of the fabric are wound about the rolls 10 the accumulation of the coils may tend to increase the tension of the outermost coils, but this tension may be relieved by placing one or more of the rolls at the outside of the coils instead of inside, as will be apparent upon observing the position of the rolls 10^a mounted in the lower portion of the the passage 13. 80

In some cases it may be desirable to expose the fabric traveling within the passage 13 to a gas confined within the passage, in which case it may be desirable to provide an air tight liquid seal at the points where the fabric enters and leaves the chamber. Means to this end is shown in the modified construction of Fig. 3 wherein it will be seen that the fabric F passes from the roll 20 around a roll 31 and then downwardly about a roll 32 positioned below the surface of the liquid confined in the receptacle 33. One portion of the wall 14 is secured to the receptacle 33 while another portion of the wall extends downwardly into the receptacle 100 33, the arrangement being such that the liquid within the receptacle 33 prevents the gas from escaping from the passage at the point where the fabric enters the passage. The fabric F in leaving the chamber 13 passes through a similar air-tight liquid seal formed by the receptacle 34. In the construction shown in Fig. 3 the supply of fabric 11 is mounted on a wheel truck 35 so that it may be easily moved to and from the 105 unwinding position.

In the construction shown and described the fabric passes from a source of supply to the inside of the traveling coils and issues from the outer face of these coils, but this is not necessary in all embodiments of the invention since if desired the fabric may travel in the opposite direction so that it is led to the outermost coil and issues from the innermost coil. It is important to note that irrespective of the direction in which the fabric F travels within the treatment chamber, each portion of the fabric will remain in such chamber the same length of time as every other por- 110 115 120 125 130

tion, thus insuring uniform treatment of all portions of the fabric.

The coil supporting structure forming the subject matter of the present invention 5 may be employed for various purposes and the fabric may be subjected to a liquid, gaseous or heat treatment while traveling in the passage 13, or it may be passed around the supporting rolls 10 to allow a 10 definite interval of time to elapse between successive treatments of the traveling fabric, one of the treatments being effected before the fabric reaches the supporting rolls 10 and the other treatment being effected after 15 it leaves the rolls 10. The time interval just mentioned may be varied as desired by varying the speed at which the rolls 10 are driven and also by increasing or decreasing the 20 number of layers of the fabric wound upon the rolls 10.

What is claimed is:—

1. The method of advancing a sheet of fabric to subject successive portions thereof to a time treatment of equal duration, which 25 consists in feeding a sheet of fabric from a centrally disposed source of supply along a path that surrounds the source of supply so that the fabric passes repeatedly around said path to form a plurality of layers laid one 30 over the other and which travel progressively from the point at which the sheet enters said path to a point at the opposite side of the traveling layers and at which the sheet issues from said path.

35 2. The method of advancing a sheet of fabric to subject successive portions thereof to an uniform time treatment, which consists in feeding a sheet of fabric from a source of supply along a path that surrounds 40 the source of supply so that the fabric passes repeatedly around said path to form spirally wound contacting layers that travel progressively from the point at which the sheet enters said path to a point at the opposite 45 side of the traveling layers and at which the sheet issues from said path.

50 3. The method of advancing a sheet of fabric to subject successive portions thereof to an uniform time treatment, which consists in feeding a plurality of spirally wound contacting layers of the fabric as a unit along a path that surrounds a central point so that each portion of the fabric enters the path at a predetermined point at one side of the path 55 and travels spirally from one layer to the other until it completes its travel between the layers and issues from the opposite side of the traveling layers of fabric.

60 4. The method of advancing a sheet of fabric through an endless passage, which consists in feeding a sheet of fabric from a source of supply into an enclosure constructed to form an endless passage and along the passage so that the fabric passes repeatedly 65 around the passage to form spirally wound

layers that travel progressively from the point at which the sheet enters the passage to a point at the opposite side of the traveling layers and at which the sheet issues from the passage.

70 5. The method of advancing a sheet of fabric to subject successive portions thereof to a time treatment of equal duration, which consists in feeding a sheet of fabric from a source of supply along a path that surrounds a central point so that the fabric passes repeatedly around said path to form spirally wound contacting layers that travel as a unit relatively to the fabric supports along said path, and advancing the fabric sheet 75 progressively from the point at which it enters said path along the different layers to a point at the opposite side of the traveling layers where it leaves said path.

80 6. A fabric advancing device, comprising in combination, a fabric support adapted to have a plurality of layers of the fabric wound around the support one over the other in contact with each other, means for advancing the coils as a unit around said support and for feeding fresh portions of the fabric to the innermost coil from a point within the fabric support and for leading the wound fabric sheet off from the outermost coil.

85 7. A fabric advancing device, comprising in combination, a fabric support adapted to have a plurality of layers of the fabric wound spirally around the support one over the other in contact with each other throughout the different coils, means for advancing the coils as a unit around said support and for leading fresh portions of the fabric to one face of the advancing coils and for leading the wound sheet off from the opposite face 90 of the advancing coils so that each portion of the sheet travels progressively along the different coils.

95 8. A fabric advancing device, comprising in combination, a series of fabric supporting rolls mounted in spaced relation to each other about a central point to support a plurality of coils of the fabric wound about the group of rolls one upon the other in superimposed contacting coils that surround said point, and means for feeding successive portions of the fabric sheet from a source of supply to said rolls so that they advance about the rolls from one coil to the other until they issue from the opposite face of the 100 coils from which they approached the same.

105 9. A fabric advancing device, comprising in combination, a series of fabric supporting rolls mounted in spaced relation to each other about a central point to support a plurality of coils of the fabric wound upon the group of rolls and about said point in contacting spiral layers, and means for feeding successive portions of the fabric sheet from a source of supply to said rolls so that the 110

portions of the sheet travel about the rolls and advance spirally from one coil to the other until they issue from the opposite face of the coils from which they approached the same.

10. A fabric advancing device, comprising in combination, a series of fabric supporting rolls arranged about and in spaced relation to a source of fabric supply and adapted to have the sheet of fabric wound around the series of rolls in superimposed coils, means for supporting the source of fabric supply within the space enclosed by the coils of fabric wound upon said rolls, and means for advancing successive portions of the sheet of fabric from the source of supply to the innermost coil supported by said rolls and along the successive coils until each portion of the sheet issues from the outermost coil 20 of the series.

11. A fabric advancing device, comprising in combination, a series of fabric supporting rolls arranged about and in spaced relation to a source of fabric supply and adapted to have the sheet of fabric wound around the series of rolls in superimposed coils, means for supporting the source of fabric supply within the space enclosed by the coils of fabric wound upon said rolls, and means for advancing successive portions of the sheet of fabric from the source of supply to one face of the group of coils supported by said rolls and along the successive coils until each portion of the sheet issues from the opposite face of the series of coils, and means for driving the rolls to feed the fabric they engage.

12. A fabric advancing device, comprising in combination, a series of fabric supporting rolls mounted about and in spaced relation to a central point and adapted to support a plurality of coils of the fabric wound about the group of rolls in contacting layers, which help to hold the successively laid coils in a transversely stretched condition, and means for advancing the series of layers as a unit about the rolls so that each portion of the fabric led into contact with one face of the traveling coils passes along the successive coils until it issues from the opposite face of the series of coils.

13. A fabric advancing device, comprising in combination, a guide for a traveling sheet of fabric, a series of fabric supporting rolls mounted about and in spaced relation to said fabric guide and adapted to support a plurality of coils of the fabric wound around the series of rolls in superimposed contacting layers so that the coils surround said guide, and are advanced as a unit about the different supporting rolls, and means for feeding successive portions of the sheet of fabric from said guide to the innermost coil supported by said rolls and along the successive

coils until each portion of the sheet issues from the outermost coil of the series.

14. A fabric advancing device, comprising in combination, a source of fabric supply supported by the floor of a building, a series of fabric supporting rolls mounted above and below the floor of the building and about said source of supply and arranged to support a plurality of coils of the fabric wound spirally about the series of rolls so that the coils surround the source of fabric supply and pass above and below said floor, and means for advancing the plurality of coils as a unit about said rolls so that the successive portions of the fabric pass from the source of supply to the innermost coil supported by the rolls and along the spiral coils until they issue from the outermost coil.

15. A device of the class described, comprising in combination, a casing constructed to provide an endless passage, rolls within said passage and adapted to support a plurality of coils of a fabric wound around the passage upon said rolls, means for advancing the plurality of coils as a unit within said passage so that the successive portions of the fabric pass from the source of supply into said passage and progressively from one coil to the other until they issue from the opposite face of the coils.

16. A device of the class described, comprising in combination, a casing constructed to provide an endless air-tight passage, rolls within said passage and adapted to support a plurality of coils of a fabric wound around the passage upon said rolls, means for advancing the plurality of coils as a unit within said passage so that successive portions of the fabric pass progressively from one coil to the other until they issue from the opposite face of the coils, and means at the points where the fabric enters and leaves said passage and adapted to prevent gaseous fluid within said passage from escaping at the fabric entrance and exit.

17. A fabric advancing device, comprising in combination, a series of fabric supporting rolls spaced apart a sufficient distance to form an enclosure in which a workman may remain during the fabric advancing operation and having a plurality of layers of the fabric wound around the series of rolls in overlying coils, means for advancing the coils as a unit around the path defined by said rolls, and means for feeding fresh portions of the fabric to the path at one face of the series of coils and for leading the wound sheet off from the opposite face of the traveling coils.

In testimony whereof, I have signed my name to this specification.

HAROLD I. HUEY.
